CLAIM

The ornamental design for a camera with gimbal, as shown and described.

DESCRIPTION

This application is the following U.S. Design Patent Application Nos., also filed on Jun. 26, 2018, each of which is also incorporated herein in its entirety by reference thereto:

29/654,658, titled "Aerial Vehicle"

29/654,662, titled "Battery"

29/654,663, titled "Camera"

FIG. 1 is a top front perspective view of a camera with gimbal showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the camera with gimbal that form no part of the claimed design.

1 Claim, 4 Drawing Sheets
